CLAIM

(21) Appl. No.: **29/156,158**

The ornamental design for “surface structures for light transmitting bodies, especially of building glass”, as shown and described.

(22) Filed: **Feb. 22, 2002**

DESCRIPTION

(30) **Foreign Application Priority Data**

FIG. 1 shows a top view of the surface structure of the light-transmitting body in one embodiment.

Aug. 22, 2001 (DE) 4 01 07 607

FIG. 2 shows a sectional view taken along line 2—2 in FIG. 1; and,

(51) **LOC (7) Cl.** **25-01**

FIG. 3 shows a an enlarged perspective view of a portion of the light-transmitting body.

(52) **U.S. Cl.** **D25/110**
